(57) **CLAIM**

The ornamental design for a tire tread, as shown and described.

DESCRIPTION

FIG. 1 is a perspective view of a tire tread showing my design;

FIG. 2 is a front view thereof;

FIG. 3 is a top view thereof;

FIG. 4 is a right side view thereof;

FIG. 5 is a left side view thereof;

FIG. 6 is a fragmentary enlarged front view showing the detail of the tire tread thereof;

FIG. 7 is a section view taken along line 7-7 in FIG. 6; and, FIG. 8 is a section view taken along line 8-8 in FIG. 6.

The broken lines are used to show portions of the tire that are not being claimed.
